WHEEL COVER TOOL

Everett L. Forstrom and Henry J. Schumacher, Winona,
Minn., assignors to Vulcan Manufacturing Co., Inc.,
Minneapolis, Minn., a corporation of Minnesota

Filed July 7, 1958, Ser. No. 51,665

Term of patent 14 years

(Cl. D93—4)

FIG. 1 is a perspective view of a wheel cover tool showing our new design;

FIG. 2 is a top plan thereof.

FIG. 3 is a side elevation thereof with a portion of the handle broken off to conserve space on the drawing; and

FIG. 4 is a rear elevation thereof with a portion of the handle broken off.

The front of the tool head not disclosed is substantially plain. The dominant feature of our design for a wheel cover tool resides in the head portion, said portion being characterized by the particular peripheral configuration of the flattened side areas as best shown in FIGS. 1 and 3.

We claim:

The ornamental design for a wheel cover tool, substantially as shown and described.
